UNITED STATES PATENT OFFICE.

RODOLPHE W. E. CHRISTESEN, OF NEW BRITAIN, CONNECTICUT, ASSIGNOR
TO THE RUSSELL & ERWIN MANUFACTURING COMPANY, OF SAME PLACE.

DESIGN FOR A LOCK-CASE.

SPECIFICATION forming part of Design No. 19,188, dated July 2, 1889.

Application filed May 31, 1889. Serial No. 312,793. Term of patent 14 years.

To all whom it may concern:

Be it known that I, RODOLPHE W. E. CHRISTESEN, a citizen of the United States, residing at New Britain, in the county of Hartford and State of Connecticut, have invented and produced a new and original Design for a Lock-Case, of which the following is a specification, reference being had to the accompanying drawings, forming part thereof.

Figure 1 is a face view of one side of a lock-case showing my design, and Fig. 2 is a corresponding view of the reverse side.

The leading feature of my design consists in a group or groups of rounded knobs or bosses upon a raised figure.

A is one side of the lock-case, and B is the reverse side, each side having the ordinary key-hole C. Upon the side A, I form three raised figures 3 3 3, having a scalloped outline, and immediately inside of the scallops and concentric therewith I arrange a circular series of bosses 4, and in the center of said figures a central boss 5, all as shown. On the reverse side B, I form around the key-hole C a raised

figure 6, having mainly a scalloped outline 25 and provided with a group or series of bosses 7, as shown. The contour of this figure is plainly shown in Fig. 2, and within said contour I form four sunken panels 8, composed mainly of curved lines, as shown. 30

What I claim is—

1. The design for a lock-case herein shown and described, the same comprising the side A, having the raised figure with scalloped outline and group of bosses within said outline, 35 and the reverse having the raised figure about the key-hole with a group of bosses thereon, as set forth.
2. In the design for a lock-case herein shown and described, the side A, having the raised figure with scalloped outline, the circular group of bosses concentric therewith, and the central boss, as set forth. 40

RODOLPHE W. E. CHRISTESEN.
